AUTOMATIC FILLING DEVICE FOR OIL RESERVOIRS OR THE LIKE

William J. Madden, Lansdowne, Pa.

Application December 2, 1932. Serial No. 645,388

7 Claims. (Cl. 137—68)

This invention relates to automatic filling devices. While capable of a variety of uses, the invention is especially useful in its application to oil reservoirs wherein it is desired to maintain a constant oil level. For example, electric motors require periodic replenishment of their oil wells, and the task of inspecting and refilling a number of such motors at frequent intervals requires considerable time and attention on the part of a skilled operator.

The object of the present invention is to provide an automatic filling device for maintaining a constant level in oil reservoirs or the like, which device is of inexpensive and simple construction and readily applied to the apparatus to be lubricated, and requires only occasional attention over a long period of time.

A more specific object of the invention is to provide a filling device of this nature designed to occupy normally an upright position with relation to the reservoir to be filled and swingable about a pivotal connection with the apparatus to be lubricated, the filling device being so constructed and arranged as to maintain a tight seal at such pivotal connection under all conditions.

Another more specific object of the invention is to provide means for cutting off gravity flow between the filling device and the reservoir to which it is attached, when the device is swung about its pivotal connection for the purpose of filling, without resorting to the use of valves or other moving parts.

Still other objects and advantages characteristic of my invention will become more fully apparent from the description hereinafter set forth of one embodiment or example of the invention, having reference to the accompanying drawings. Of the drawings:

Fig. I represents a side elevation of a portion of an electric motor with an oil filling device of my invention applied thereto.

Fig. II represents a cross section of the same, taken as indicated by the lines II—II of Fig. I.

Fig. III represents a cross section of the oil filling device, taken as indicated by the lines III—III of Fig. II; and,

Fig. IV represents a perspective view of a socket forming a connection between the oil reservoir of the motor and the filling device.

While my invention may take a variety of forms and is applicable to the filling of many different types of reservoirs, I have selected for illustration an example wherein the filling device is applied to an oil well of an electric motor 1. Motors now

commonly used for driving fans, blowers or the like contain oil wells such as represented at 2 in Fig. II. The motor shaft is designated at 3 and has thereon a ring 4 which acts as a distributor bringing oil from the bottom of the well to the motor shaft 3 and thence to its bearings 5. The desired level of oil in the well 2 is indicated at 6.

In applying the device of my invention to the motor 1, I employ a socket 7, shown in perspective in Fig. IV, which has thereon a threaded projection 8 engaging a correspondingly threaded opening 9 in the side of the oil well 2. At its opposite end the socket 7 is provided with an annular flange 10 engaged by an internally threaded cap 11. To the threaded cap 11 there is applied the auxiliary oil container 12 hereinafter more specifically described.

The oil container 12 is preferably L-shaped, as appears in Fig. I, and includes a vertical arm 13 comprising a sealed chamber and a horizontal arm 14 at substantially a right angle therewith through which the container may be filled. At the base of the container and formed integrally therewith there is a discharge duct 15 in the form of a stem projecting laterally toward the oil well 2. The discharge duct 15 terminates in a fitting 16 which includes an externally threaded portion engaged by the cap 11 on the socket 7. The fitting 16 also includes a plug 17 which fits snugly within the cylindrical bore 18 of the socket 7. A ring 19 of compressible packing occupies the space between the base of the cylindrical bore 18 and a shoulder near the end of the plug 17. The packing ring 19 forms a seal preventing leakage of oil at the joint. The discharge duct 15 defines a discharge passage 20, which leads to the oil reservoir 2, the top whereof is coincident with the oil level, as represented at 6, which is the level desired to be maintained in the oil well.

By virtue of the construction described, it will be apparent that there is a pivotal connection between the auxiliary oil container 12 and the socket 7, and that the container 12 is adapted to rotate with respect to the socket 7 about the axis of the discharge duct 15. As illustrated in Figs. I—III, the oil container 12 normally occupies a substantially upright position with the top thereof canted to one side. The overbalancing weight of the container at that side tends to rotate the container in a clockwise direction about the axis of the discharge duct 15, and this in turn tends to screw the fitting 16 into the threaded cap 11, thus compressing the packing ring 19 and maintaining a tight seal at the socket 7.

At the base of the container 12, the discharge duct 15 extends inward as represented at 21 and merges with an extension duct 22. The extension duct 22 projects at a right angle with the discharge duct 15 through the horizontal arm 14 of the container 12 and preferably terminates in a reduced end 27 near the mouth of the filling opening 23 at that portion of the container. At the filling opening 23 there is a removable threaded cap 24 preferably on its exterior surface. The cap 24 includes a window 25 of glass or other transparent material, and suitable gaskets 26 at the marginal edges of the same. Accordingly, the cap 24 serves not only as a closure for the filling opening 23, but serves also as a sight gauge indicating the level of the oil within the container 12 when that level drops below a certain point.

It will be noted that the container 12 normally occupies the position shown in full lines in Fig. I, but that it is adapted to be swung in a counter-clockwise direction to the position indicated in broken lines in that figure. When it is desired to refill the container 12, the container is swung from the upright to the horizontal position shown in dot-and-dash lines in Fig. I. In the latter position the extension duct 22 is substantially vertical and extends upward to a point above the topmost portion of the arm 14, thus cutting off gravity flow between the container 12 and the oil well 2.

The operation of the oil filling device described above is as follows. When it is desired to fill the container 12, the container is rotated in a counter-clockwise direction to the position shown in dot-and-dash lines in Fig. I. In this position the arm 13 is conveniently held in one hand while the cap 24 at the filling opening 23 is removed with the other hand. With the cap 24 removed, oil is poured into the container filling the same to the top level corresponding to the top of the extension duct 22, and the cap is then screwed on. Having filled the container 12, the operator swings the container in a clockwise direction to its normal upright position. Oil is then free to flow through the extension duct 22 and the discharge duct 15 into the oil well 2, but this flow will only continue until oil in the oil well 2 reaches the level indicated at 6. Further flow is prevented because the container 12 is sealed against the admission of air. As the oil in the motor well 2 is dissipated with the use of the motor, the level of oil in the well will be maintained at the desired point, for any reduction in the oil level is accompanied by an admission of a small amount of air into the container, which in turn results in the simultaneous escape of a few drops of oil, and hence causes the return of the oil level to the proper elevation.

It will be especially noted that during the filling operation oil can be poured into the container without the danger of its flowing into the motor oil well, it being most important that an excess of oil should not be admitted to the oil well. The cutting off of gravity flow between the oil container 12 and the oil well 2 during the filling operation is accomplished by means of the special relation of the extension duct 22 to the arm 13 of the oil container. Accordingly, in contrast to other forms of oil filling devices, the device of my invention does not utilize, or depend for its operation upon, valves or other moving parts, but it is of simple and reliable construction and is manipulated with ease and facility.

While I have described one form which my invention may take, it will be apparent that various changes may be had in the form of the device herein described, without departing from the spirit of my invention as defined in the annexed claims. Such contemplated changes relate, for example, to the nature of the swivel joint between the container and the reservoir to be filled, the shape of the container, and the location of its filling opening.

Having thus described my invention, I claim:

1. A filling device for replenishing oil reservoirs or the like comprising a container having a discharge duct projecting from the base thereof, said discharge duct terminating in a fitting adapted for pivotal connection to the reservoir to which the device is applied, a filling opening at one side of the container, and a duct within the container forming an extension of the discharge duct and leading to the side of the container upon which the filling opening is located.

2. A filling device for replenishing oil reservoirs or the like comprising a container having a discharge duct projecting from the base thereof, said discharge duct terminating in a fitting adapted for pivotal connection to the reservoir to which the device is applied, a filling opening at one side of the container, and a duct within the container forming an extension of the discharge duct and leading to the side of the container upon which the filling opening is located, said extension duct being of such length and disposed at such an angle with the axis of the container that when the container is swung downward from a normally upright position to a position in which the filling opening is at the top of the container the extension duct will cut off gravity flow between the container and the discharge duct.

3. A filling device for replenishing oil reservoirs or the like comprising a container having a stem formed integrally therewith and projecting from the base thereof, said stem including a fitting adapted for pivotal connection to the reservoir to which the device is applied, a discharge passage through said stem, a filling opening at one side of the container, and a duct within the container forming an extension of the discharge passage, and leading to the side of the container upon which the filling opening is located.

4. A filling device for replenishing oil reservoirs or the like comprising a socket at an opening in the reservoir to be replenished, a container having an integral discharge duct projecting from the base thereof, said discharge duct terminating in a threaded plug engaging within said socket, compressible packing disposed within said socket and adapted to seal the space between said plug and the opening in the reservoir, and a filling opening at one side of the container, said container and its threaded plug being so applied to the reservoir socket that in its normal position the top of the container is canted toward the side which contains the filling opening with its weight thereby tending to rotate said plug and compress said packing.

5. A filling device for replenishing oil reservoirs or the like comprising a socket at an opening in the reservoir to be replenished, a container having an integral discharge duct projecting laterally from the base thereof, said discharge duct terminating in a threaded plug engaging within said socket, compressible packing disposed within said socket and adapted to seal the space between said plug and the opening in the reservoir, a duct within the container forming an extension of

the discharge duct and leading to one side of the container, said container and its threaded plug being so applied to the reservoir socket that in its normal position the top of the container 5 is canted toward the side containing the extension duct with its weight thereby tending to rotate said plug and compress said packing.

6. A filling device for replenishing oil reservoirs or the like comprising an L-shaped container 10 having a discharge duct projecting from the intersection between the two arms thereof, said discharge duct terminating in a fitting adapted for pivotal connection to the reservoir to which the device is applied, one arm of said container 15 constituting a closed chamber and the other arm of said container terminating in a filling opening, a removable cap for closing said filling opening, and a duct within the container forming an extension of the discharge duct and leading 20

through said latter arm toward the mouth of the filling opening.

7. A filling device for replenishing oil reservoirs or the like comprising an L-shaped container having a discharge duct projecting from the intersection between the two arms thereof, said discharge duct terminating in a fitting adapted for pivotal connection to the reservoir to which the device is applied, one arm of said container constituting a closed chamber and the other arm of 80 said container terminating in a filling opening, a removable cap for closing said filling opening, and a duct within the container forming an extension of the discharge duct and leading through 85 said latter arm toward the mouth of the filling opening, said removable cap including a transparent member serving as a sight gauge for indicating the level of fluid in the container.
